UNITED STATES PATENT OFFICE.

EDWARD S. MADDOCK, OF KENOSHA, WISCONSIN, AND JOSEPH M. COBB, OF CHICAGO,
ILLINOIS.

RECORD-CARD.

1,029,702.

Specification of Letters Patent. Patented June 18, 1912.

Application filed September 26, 1911. Serial No. 651,379.

To all whom it may concern:

Be it known that we, EDWARD S. MADDOCK and JOSEPH M. COBB, both citizens of the United States, and residents, respectively, 5 of Kenosha, in the county of Kenosha and State of Wisconsin, and of Chicago, in the county of Cook and State of Illinois, have invented certain new and useful Improvements in Record-Cards, of which the following is a specification.

The invention relates to a record card for use in card indexes or any other card record system.

The principal object of the invention is 5 to provide a record card with a pointer or index removably secured thereto, the pointer or index and its means of adjustable securing to the card being such that the card may be removed from or restored to 10 its place among other cards without danger or liability of displacing the pointer or index.

A further object of the invention is to provide an improved record card with removable indexes whereby the dates of entries upon such cards, or upon other cards associated therewith, or the date or dates for future entries or notations, or other indicia relating to the contents of the cards, 15 may be pointed out and readily ascertained by reference to the position of the indexes upon said cards.

Practical embodiments of the invention are shown in the accompanying drawing, in which—

Figure 1 is a side elevational view of our improved record card. Fig. 2 is a top edge view of Fig. 1. Fig. 3 is a horizontal sectional view on the line 3—3 of Fig. 1. Fig. 4 is an enlarged fragmentary view, more particularly illustrating the pockets for containing the indexes. Fig. 5 is an enlarged vertical section through one of the index pockets, showing an index therein. Figs. 6 and 7 are views corresponding with views 4 and 5, respectively, showing a modified form of index.

Referring to Figs. 1 to 5 inclusive, *a* designates the card as an entirety, the same consisting of three plies of paper *b*, *c*, and *d*, which are suitably secured together, the central ply *e*, being formed with a series of comb-like tongues *e*, so that when the three plies are united a series of pockets *f* are formed between adjacent tongues. Prefer-

ably, and as herein shown, the outer ends of the tongues *e* extend slightly above or beyond the edges of the outer plies *b* and *d*, to more clearly indicate the positions of the upper ends of the pockets *f*.

The pointer or index, in its preferred form, consists of a thin spear-shaped strip comprising a stem or shank *g* adapted to have a sliding fit within any one of the pockets *f*, and a triangular shaped head *h* 60 at its upper end normally projecting above the upper edge of the card and readily disclosing the position of the index. One or more of these indexes may be employed, as desired. On either or both sides of the 70 card and directly opposite the respective pockets are provided a series of numerals *i*, such as 1 to 31 inclusive, to indicate daily dates for a month, or any other classification or character of reference desired.

It will be noted that the pointers or indexes are of somewhat less thickness than the total thickness of the card, or at least the thickness of these indexes does not exceed that of the card, so that when two or 80 more cards of the character herein shown are placed together, that is, side by side, no part of the pointer or index protrudes on, either side of the card to which it is attached, and will not, therefore, catch upon 85 adjacent cards so as to be displaced or so as to interfere with or displace the pointers or indexes of adjacent cards.

In Figs. 6 and 7 we show a modified form of index or pointer consisting of a flat strip 90 of metal or other suitable material *j* doubled upon itself, the free ends being slightly separated to form a spring, and we preferably provide in the body of said bent strip a laterally off-set portion or crimp *k*, so as 95 to better retain the indexes frictionally within the pockets. Each record card may be numbered, if so desired, and may be used independently of or in association with other cards, the manner of use being substantially as follows: Assuming that a certain subject matter as indicated on the face of the card requires action or attention on a certain future date, entry of such subject matter is either made upon the record card 100 or upon a card or slip attached to and accompanying the same, and the index is then placed within the pocket on the edge of the card bearing the date of the month upon which the matter is to receive attention. 110

By reference to the files each day, if necessary, one can quickly and easily ascertain from the position of the indexes the exact day or days when attention must be given 5 to the matter or the exact date when attention was last given or action was last taken, according to how the indexes are used in the particular matter in which they are employed. Notations or entries may be made 10 upon the cards themselves, and the indexes used to indicate the date of the last entry or action, or the date of future entries or actions, according to the system used, the purpose of the indexes being to indicate a specific 15 time when something has been done or is to be done relating to the subject matter borne by the card, or to indicate some other desired class of reference to the contents of the card. Although we have shown the 20 card as bearing numbers indicating dates as of the days of the month, it will be understood that such particular classification is not of the essence of the invention, since alphabetical, geographical or other classifications may be employed. 25

The precise form of the index pointer or the material of which it is made is not material, nor the number of such indexes used upon a card, provided they are, mechanically, of such form and structure as to be free from liability to accidental displacement or interference with adjacent cards of the series.

Therefore, without limiting ourselves to 30 the precise details of structure herein shown, we claim:

1. A record card, in combination with an

index adapted to be secured at any of a number of predetermined positions on said card, said index when in operative position lying 40 wholly between the planes of the sides of the card.

2. A record card having a plurality of pockets formed in one edge thereof, in combination with an index adapted to fit in any 45 one of said pockets.

3. A record card having a plurality of pockets formed in one edge thereof, in combination with an index of a thickness not exceeding that of said card and adapted to 50 fit in any one of said pockets.

4. A record card having a plurality of pockets formed in one edge thereof, in combination with a thin index adapted to slidingly fit any one of said pockets and projecting above the upper edge thereof, said index lying wholly between the planes of the opposite sides of the card in which said 55 pockets are formed.

5. A record card formed with three plies 60 of paper adhered together, the intermediate ply being formed along its upper edge with a plurality of parallel tongues, thereby creating between the outer plies and between adjacent tongues a plurality of pockets, in 65 combination with indexes slidably engaging and at their upper ends projecting above said pockets.

EDWARD S. MADDOCK.
